DRAFTSMANS' TRIANGLE

Clyde C. Johnson, 1824 Marcella St., Simi, Calif.

Filed Oct. 12, 1965, Ser. No. 87,466

Term of patent 14 years

(Cl. D52—6)

FIGURE 1 is a plan view of a draftsmans' triangle showing my new design;

FIGURE 2 is a side elevational view;

FIGURE 3 is a side elevational view;

FIGURE 4 is a bottom elevational view;

FIGURE 5 is a top elevational view;

FIGURE 6 is a sectional view taken at line 6—6 of FIGURE 1; and

FIGURE 7 is a back plan view.

I claim:

The ornamental design for a draftsmans' triangle, as shown.
